UNITED STATES PATENT OFFICE.

DANIEL J. MURNANE, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

STORE-FRONT CONSTRUCTION.

Application filed December 2, 1921. Serial No. 519,407.

To all whom it may concern:

Be it known that I, DANIEL J. MURNANE, a citizen of the United States, residing at 2606 Chicago Road, Chicago Heights, Illinois, in the county of Cook and State of Illinois, have invented a new and useful Improvement in Store-Front Constructions, of which the following is a specification.

My invention relates more particularly to 10 that portion of a store-front construction which extends adjacent the sill at the window opening to be equipped with a store-front construction used for holding sheets of glass in place; and my object is to provide 15 a novel, simple and inexpensive arrangement of the clamping members, between which the sheets of glass are to be clamped, and the means for securing these clamping members in position on the sill.

20 Referring to the accompanying drawing:-

Figure 1 is a view in sectional elevation of a store-front construction constructed in accordance with my invention, and showing a 25 sheet of glass secured in position therein, a portion of the said sheet and the sill upon which a part of the store-front construction shown, is supported, being shown in section, the section being taken at the line 1 on Fig. 30 2 and viewed in the direction of the arrow. Figure 2 is a section taken at the line 2 on Fig. 1 and viewed in the direction of the arrow; and Figure 3, a section taken at the line 3 on Fig. 2 and viewed in the direction 35 of the arrow.

It may be stated as a premise to the following description of the construction to which my invention relates, that it is formed of clamping strips or sections which extend 40 substantially parallel with each other and between which the sheet of glass to be secured extends, means whereby these strips are drawn relatively toward each other to clamp the sheet between them, and means 45 for securing to the sill one of said strips which extends at the inner surface of the sheet of glass, it being my primary object to provide for the proper securing of this inside strip to the sill and the reinforcing 50 of this strip by simple and inexpensive means, the entire assembly being such that these securing means cannot be seen by one looking down upon the construction, or one viewing it from the exterior surface of the 55 store-front construction.

In accordance with the particular illustrated embodiment of my invention, the two parallel strip members referred to and between which a sheet of glass, shown at 4, is clamped at its lower edge, are represented 60 generally at 5 and 6, these members being formed of sheet metal rolled, or otherwise bent, into the desired cross sectional shape and extending the full length of the sill, represented at 7. The strip 5 is shown as 65 providing a rearwardly extending flange 8 at its lower edge and a rearwardly extending flange 9 at its upper edge, the latter terminating in a depending lip 10. The strip member 6 is shown as provided with a forwardly extending flange 11 at its lower edge, 70 which overlies the top of the sill 7 and upon which the flange 8 is superposed and with relation to which the member 5 is slidable crosswise of the length of the strips referred 75 to. The strip 6 is also provided at its upper edge with a forwardly extending flange or plate-like portion 12 provided at its forward edge with a depending lip 13, this strip being so shaped, as for example as 80 shown, as to provide a rearwardly offset hollow bead-like portion 14 at its upper edge with a portion of the strip 6 extending below it, and affording a recess or channel 15 extending preferably the full length of the 85 construction now being described at the rear side of the structure.

The sheet 4 of glass extends into the space between the lips 10 and 13, at which portions the sheet 4 is clamped in place with the desired pressure, by relative movement of the parts 5 and 6, this relative movement being effected by means as hereinafter described, the strip member 6 in the construction shown 90 being rigidly secured to the sill. 95

The means for securing the member 6 to the sill are shown as formed of an angle iron 16 which flatwise opposes at its section 17, the sill 7 to which latter it is secured at intervals, as for example, by screws represented at 18, the upwardly extending portion 17^a of the angle iron 16 extending into the recess 15 and flatwise opposing at its front surface, the rear surface of the adjacent upwardly extending rear portion of 100 the strip section 6, and at its upper surface flatwise opposing the underside of the bead 14, and forming a bearing surface for the latter, the section 6 being rigidly secured to the portion 17^a of the angle iron, as by any 105 110

suitable means, such as rivets located at intervals along the angle iron and extending through apertures 17° in the portion 17, one of these rivets being indicated at 19.

5 The means shown for drawing the strip member 5 toward the strip member 6 to clamp the sheet 4 of glass between these strip sections 5 and 6, comprise a series of bracket members 20 located at intervals 10 within the strip section 6, these bracket members being each formed with an upwardly extending portion 21 rigidly secured to the strip section 6 and the angle iron 16, as for example by a rivet 19 which is shown as 15 passing through all three of these members. Each of the brackets 20 also comprises a forwardly extending portion 22 at the upper edge of the portion 21, which abuts the rear surface of the depending lip 13, 20 the lateral edges of the portion 22 being bent to form tubular portions 23. The portions 22 are apertured as represented at 24 and in each aperture a bushing 25 is located and interlocked, this bushing containing a vertically disposed threaded opening 26 extending entirely therethrough and in which a screw device 27, having its lower end of conical shape as represented at 28, is threaded. The portion 12 of the strip section 6 is apertured at intervals as represented at 29, these apertures extending directly above the several screw devices 27 and serving to permit of the application of a suitable tool to the upper end of the 35 screws 27 to rotate them in the bushings 25. Supplementing the rivets 19, for holding the brackets 20 in place, are bodies 30 of cast metal, such for example as lead, which is poured into the tubular portions 23 and 40 interlocks with the depending lip 13 and the rear portion of the member 6. This is accomplished in the construction shown by providing in the lip 13 and the rear portion of the member 6 at parts thereof in 45 registration with the ends of the tubes 23, openings 31 and 32 which preferably flare outwardly as shown, the molten metal being poured for filling not only the tubes 23 but also the apertured portions 31 and 32 50 of the member 6.

Cooperating with the screw devices 27 are members, one of which is represented at 33, one of these members being provided for cooperation with each of the screw devices 55 27, these members being preferably of the shape shown and each comprising the substantially flat portion 34 at which it superposes the portion 8 of the strip member 5 and an upwardly extending portion 35 at 60 its forward edge extending in the rear of the front portion of the member 5. The portion 35 is provided at opposite edges with rearwardly-extending flanges one thereof being shown at 36", the upper edges 65 of these flanges opposing the front surface

of the depending lip 10. The member 33 also comprises a rearwardly-extending portion 37 of general triangular shape in cross-section affording at its lower end, the forwardly extending portion 38 at which it 70 rests upon the forwardly extending flange 11 of the part 6, and is also formed with an upwardly and rearwardly inclining portion 39 located directly below the screw 27 and against which the latter, at its lower 75 conical surface, bears.

It will be understood from the foregoing that as the strip member 6, the brackets 20 and the bushings 25 are firmly held in position on the sill by the angle iron 16, the rotation of the screw devices 27 in a direction to cause them to lower in these bushings, will operate to force the member 33 to the right in Fig. 1 and by reason of their engagement at their flanges 36 with the lip 10 of the member 5, force the latter bodily to the right in this figure, this member sliding along the flange 11, and clamping the sheet 4 of glass between the depending lips 10 and 13.

It will be noted that the provision of the recess, or channel, 15 at the rear side of the strip section 6 serves to prevent the securing-member 16, from being seen when one is looking down on the structure or viewing it from the exterior, thus permitting of the employment of this very desirable means for the securing of the member 6 in position, without detracting from the desired appearance of the store-front construction.

The member 16 is shown as, and by preference is, of relatively thick metal, as compared with the strip 6, which latter in practice would preferably be made of relatively light gauge sheet copper, and by positioning the member 16 as shown and stated, it serves to reinforce the member 6 and minimizes danger of the latter becoming crushed, as for example should it be stepped upon.

While I have illustrated a particular construction embodying my invention, I do not wish to be understood as intending to limit it thereto as the same may be variously modified and altered without detracting from the spirit of my invention.

What I claim as new:

1. The combination with a member forming a wall of a glazed opening, of glass-plate-clamping means extending along opposite sides of the sheet of glass, said means being formed at their rear side with a plate-like portion which extends rearwardly from said sheet and at an angle thereto and lengthwise of the construction and a portion which depends from said plate-like portion and is inset forwardly from the rear edge of said plate-like portion, whereby a recess or channel is provided and an angle-iron member secured to said first-named member and extending lengthwise of said clamping 130

means, with one of its angularly-disposed portions disposed in said recess, and means engaging said clamping means with the portion of said angle-iron member located in said recess.

2. The combination with a member forming a wall of a glazed opening, of glass-plate-clamping means extending along opposite sides of the sheet of glass, said means being formed at their rear side with a plate-like portion which extends rearwardly from said sheet and at an angle thereto and lengthwise of the construction, an upwardly extending portion adjacent to the rear edge of said plate-like portion and a hollow bead-like portion which extends rearwardly above said upwardly-extending portion and is connected with the latter and with the rear edge of said plate-like portion, whereby a recess or channel is provided, and an angle-iron member secured to said first-named member and extending lengthwise of said clamping means, with one of the angularly-disposed portions disposed in said recess, and means engaging said clamping means with the portion of said angle-iron member located in said recess.

3. The combination with a member forming a wall of a glazed opening, of glass-plate-clamping means comprising relatively movable members, with means for securing them in adjusted clamping position, the one of said last-referred-to members which engages the rear side of the glass-plate being formed with a plate-like portion which extends rearwardly from said glass-plate and at an angle thereto and lengthwise of the

construction and a portion which depends from said plate-like portion and is inset forwardly of the rear edge of said plate-like portion, whereby a recess, or channel, is provided, and an angle-iron member secured to said first-named member and extending lengthwise of said plate-clamping means, with one of its angularly-disposed portions extending upwardly and disposed in said recess, and means engaging the rear one of said relatively movable clamping members with the portion of said angle-iron member located in said recess.

4. The combination with a member forming a wall of a glazed opening, of glass-plate-clamping means comprising relatively movable members, with means for securing them in adjusted clamping position, the one of said last-referred-to members which engages the rear side of the glass plate being in the form of a hollow sheet-metal body having a top portion of plate-like form which extends rearwardly from said glass plate and at an angle thereto and lengthwise of said member, and a wall supporting said plate-like portion and inset forwardly of the rear edge thereof whereby a recess, or channel, is provided, and an angle-iron member secured to said first-named member and extending lengthwise of said plate-clamping means, with one of its angularly-disposed portions disposed in said recess, and means engaging the rear one of said relatively movable clamping members with the portion of said angle-iron member located in said recess.

DANIEL J. MURNANE.
